UNITED STATES PATENT OFFICE.

IRA W. KNIGHT, OF CRANSTON, RHODE ISLAND, ASSIGNOR TO GENERAL FIRE EXTINGUISHER COMPANY, OF PROVIDENCE, RHODE ISLAND, A CORPORATION OF DELAWARE.

VALVE APPARATUS.

Application filed June 8, 1925. Serial No. 35,837.

This invention relates to improvements in valve apparatus. More particularly it relates to valve apparatus for testing the readiness of the pump to operate, in an automatic sprinkler system employing a pump for boosting the system pressure from a low pressure in the source of supply, to a high pressure in the distributing lines, whenever discharge through a sprinkler head occurs.

Booster systems make automatic sprinkler protection possible in fire risks where the supply pressure from the city main or other source is too low for effective sprinkler service, and where the structural weakness of the risk makes it impracticable or financially prohibitive to use a large gravity tank. Such systems, whether of the wet or dry pipe type, include between the supply main and the distribution pipes a normally inactive pump and control means therefor responsive to the system pressure, for starting the pump whenever a sprinkler head is opened. Reliability being of the very essence, it is highly advisable to test such systems frequently. The great cost of having experts visit each risk to make the tests locally, with desirable frequency, emphasizes the desirability to have several risks connected electrically with a central supervisory station, by a device enabling a test of any individual risk to be made by a person at that station whenever desired. Such a system is disclosed in United States Patent No. 1,504,563, granted August 12, 1924, to Albert J. Loepsinger and entitled "Supervisory device for automatic sprinkler systems and the like". The test valve apparatus illustrated and described herein is particularly adapted for use in a supervisory system such as is disclosed in that patent; but other applications of its principles are possible for operating a valve located at a distance from the operator. For automatic sprinkler systems the invention is applicable to both wet pipe and dry pipe arrangements.

An illustrative embodiment of the invention comprises a valve controlling an outlet from a sprinkler system whereby a situation may be produced simulating the conditions that would exist in the system if a sprinkler head were opened by fire. The stem of this valve is lifted by a lever which is a sort of connecting rod to translate the rotary motion of a crank into reciprocating motion

of the stem, to open or close the valve. The crank is turned through a single rotation by suitable gearing, driven by a small electric motor which starts in response to an impulse relayed from a remote central supervisory station. The crank arm is a disk whose peripheral edge constitutes a series of cam surfaces adapted during a single rotation to make and break certain circuits controlling the motor. When applied to wet pipe systems it is a feature that, during its said rotation, the disk controls other circuits connected with the water flow alarm device, to the end that the flow of water incident to the test shall not send a water flow signal to the central station, such as occurs when a sprinkler is opened by a fire, nor permit a supplementary control circuit to be made whose normal function is to maintain the pump continuously in operation once it has been started. For a dry pipe system the apparatus may be somewhat simpler because the test can be completed without unseating the dry pipe valve, and, since the latter's opening controls the alarm apparatus and supplementary circuit for continuous pump action, there need be no provision in the test valve apparatus for rendering these elements temporarily inoperative. Where the opening of the test valve promptly effects a condition analogous to one which would cause the pump to start for fire extinguishment, the movement of the cam disk can be continuous through the single rotation, but where the test valve needs to be held open awaiting the occurrence of a pre-arranged event, as for example the bleeding of the system pressure to a predetermined degree, it is a further feature to have the disk pause at the end of a half rotation, with the test valve open, and then upon the occurrence of the expected event, to continue through its remaining half rotation to close the valve and then stop until another test is initiated by the central station operator.

The present application is directed to the generic principles of the invention, and specifically to their application in illustrative apparatus having a continuously moving cam disk. In my co-pending application Serial No. 37,336, filed June 15, 1925, apparatus providing a pause during the complete rotation of the disk is disclosed and specifically claimed.

It is intended that the patent shall cover by suitable expression in the appended claims whatever features of patentable novelty exist in the invention disclosed.

5 In the accompanying drawings:

Figure 1 is an elevation of a booster pump sprinkler system of the dry pipe type embodying the test valve of the present invention, and shows more or less diagrammatically the local circuits at a risk and also the main transmitting wires connecting it and a neighboring risk with the central station;

10 Figure 2 is an elevation of the test valve of Figure 1, and actuating mechanism therefor comprising a continuously moving disk, showing the valve closed;

15 Figure 3 is a view similar to Figure 2, but with the valve shown open;

20 Figure 4 is a side view partly in section on line 4—4 of Figure 2, but with the wires omitted;

25 Figure 5 is an elevation similar to Figure 1 but showing the invention applied to a wet pipe sprinkler system;

30 Figure 6 is an elevation of the test valve of Figure 5, in closed position, showing also the valve actuating mechanism; and the additional means provided for rendering inoperative the circuits controlled by the water flow alarm valve, and

35 Figure 7 is an elevation like Figure 6, showing the position of the several parts when the disk has completed one half of its continuous rotation.

40 Referring to the drawings, Figure 1 shows diagrammatically a supervisory system extending from a central office A to distant fire risks B and C, and in more detail, the sprinkler system of the latter risk. This is of the dry type having a booster pump 10 set between a low pressure supply pipe 12 and the dry pipe valve 14, beyond which the distributing lines 16 lead to automatic sprinkler heads 18 placed in regions to be protected in case of fire. The valve 14 may be either of 45 mechanical or differential type, the latter being the kind indicated. As illustrated, the intermediate chamber of the differential valve co-operates with control apparatus whereby the pump is automatically started whenever the supply pressure enters the intermediate chamber; and this may be taken as typical of any valve having a chamber or compartment which the water enters when 50 the valve operates.

55 The automatic pump control includes two pressure responsive devices, one of which, 20, of a type actuated by fall of pressure, is connected to the system on the air side of the dry pipe valve, being shown connected to the riser 16; and the other of which, 22, is of a type actuated by rise of pressure, and is connected through a pipe 23 with the intermediate chamber 15 of the valve. Both 60 devices are electrically arranged in parallel

in a circuit *a* which includes the energizing coil of a solenoid switch 24 adapted to connect terminals *c* in another circuit *d* which includes a rheostat starter 26 for the motor 27 of pump 10. Actuation of either responsive device 20 or 22 closes the solenoid circuit, and thus brings about the operation of the pump for boosting the supply pressure

70 Ordinarily, when a sprinkler head opens the air pressure fall acts first, and through device 20 starts the pump; and then upon the opening of the dry pipe valve, with consequent rush of water into its intermediate chamber and thence through pipe 23 the pressure rise device 22 is actuated; and this 80 continues the pump in operation after the pressure fall device 20 has broken its part of circuit *a* because of pressure having risen again in the system 16. But for a mere test of the pump as to operative condition it is 85 quite desirable to leave the air side of the system undisturbed, and so the pressure rise device 22 is employed. The latter may be connected to either the water side or the air side of the dry pipe valve; and if connected 90 to the air side it takes so little from the system that its operation does not appreciably change the air pressure and does not at all approach the production of a fall sufficient to trip the dry pipe valve 14. In cases where 95 the water supply pressure may be zero, or very low, it will be preferable to connect the pressure rise device 22 of the system on the air side of the dry pipe valve. However, in the embodiment illustrated the branch connection 28 for operating this test valve is 100 represented as branching from the system on the water side of the dry pipe valve. As thus arranged it constitutes a by-passage, controlled by the test valve 32, to the pressure responsive device 22, paralleling the regular operating channel for that device which includes the intermediate chamber 15 and the pipe 23 leading thence laterally to 105 device 22.

110 This by-passage 28 joins the pipe 23 beyond a check valve 30 which permits flow from the chamber through 23, but prevents reverse flow, except that a restricted vent in its clapper permits a drainage relief from 28, 22, enough to relieve the pressure in the latter whenever the by-passage 28 pressure supply is cut off. This slight inflow to the intermediate chamber escapes by the usual drain 31 to waste, and is small enough to 115 avoid operating the usual automatic closure valve in this drain.

120 The present invention has to do with the branch passage, herein called by-passage 28, and means for opening and closing its control valve 32 with such speed and intervals of time as will make test of the operative condition of the electrical and hydraulic apparatus and supply, all from the central supervisory station at a distance.

- The stem 34 (see Fig. 2) of this valve is worked by a lever 36 pivotally mounted at one end on a casing 37, and at its free end provided with a slot 361 in which slides a 5 crank pin 38 outstanding from the flat side of a disk 40. When the latter is turned as by suitable gearing from motor 42, the lever is raised and lowered thereby effecting an opening and closing of the valve 32.
- 10 The valve motor is started, when a test is made, by the operator at the central station sending a distinctive series of impulses over the circuit L which may conveniently be done by methods well known but for which 15 only a finger key is illustrated at A which causes the selector S at the selected risk to close a switch 44 in a circuit including wire e leading from one side of the power mains M, through wire f to the motor 42 and along 20 wire g back to the other of the power mains. This circuit is closed only momentarily, because the selector S resets its switch 44 open as soon as the impulse transmission ceases. Accordingly there is provided a supplementary 25 circuit through a branch wire h leading from the wire e ahead of the selector switch 44 to one terminal 46 (Fig. 2) of a spring switch S', located in the casing 37 housing the valve motor and disk 40, and 30 having an insulated base or holder 47 through which projects the terminal 46 and another terminal 52. The latter is connected by wire i to wire f so that when the two terminals are in contact the supplementary 35 circuit is complete. The terminal 46 has a roller 48 arranged to ride on the peripheral edge of the crank disk 40. When the test valve is closed, this roller rests in a hollow or depression 50 in the disk edge 40 which allows its terminal 46 to spring away from the other terminal 52 of the switch, which latter is held back by its stop 54. During the momentary closing of the selector 45 switch S the motor starts and turns the crank disk 40 far enough for the depression 50 to leave the roller 48 and for the higher cam surface that extends continuously around the disk except for the hollow 50 to push the roller far enough to close the spring 50 switch terminals. Where these are in contact the supplementary circuit through the motor is closed, and the motor is kept running continuously until the roller again falls into the hollow, and since this is at the end of 55 the complete rotation of the crank the test valve will have been opened and closed while the supplementary circuit is maintained. I have discovered that by a suitable co-ordination of speeds of action of pressure responsive device 22, switch 24, starting box 26, and pump 10 with the speed of rotation of disk 40, it is possible during a single continuous rotation to have the valve 32 open, remain open long enough for sufficient fluid 60 pressure to reach the responsive device 22 to

operate various elements to start the pump, and cause the various supervisory signals to be sent, and then be closed to permit this by-passed pressure on device 22 to leak away and thus to stop the pump. This permits 70 the making of the valve control in the extremely simple arrangement shown with continuous rotation through the cycle of the test.

If for any reason the pump is not in working order or the water supply has failed, or the electrical power is defective, this condition is indicated at the central station by failure of any signal to arrive there from the transmitter T which sends a distinctive signal upon rise of pressure. Another test may be made at once or a personal inspection of the apparatus to find the trouble. In case of fire, when one or more sprinkler heads open, the fall of air pressure is signalled by another transmitter t and if within the proper time thereafter a signal showing the pump has started is not received from the pressure rise transmitter T the central operator can apply the key, as for a test, 90 and try thus to start the pump. Failure to do so would indicate that the system is out of order, in which case the operator would send an inspector at once to the risk. Preferably the pump is of a type which does not 95 produce pressure sufficient to open the dry pipe valve when air in the pipes is at normal pressure. When a sprinkler has opened this pressure falls steadily. If successful in starting the pump the operator can by repeating the test immediately, and still again, if necessary, maintain the boosted pressure on the dry pipe valve until the system air pressure has become sufficiently reduced by escape from the assumed opened sprinkler 100 to permit the valve to be opened by the boosted pressure. This would then be followed by a permanent actuation of the pressure rise device 22 and continuously effective 105 sprinkler discharge pressure. 110

Figures 5 to 7 illustrate the application of the invention to a wet pipe system, in which water stands in the supply pipe 12, idle pump 10, and riser 16, up to a water flow alarm valve 58. Beyond this valve the system is charged with water and incidentally entrapped air at a pressure set up by the pump during a previous period of operation. Connected to the distributing line beyond the valve is a surge tank 60 in which is entrapped air that transmits the system pressure to the control device 20, responsive to fall of pressure, as previously described, to close the circuit a through the solenoid switch 24 which in turn establishes the connection between terminals c and starts the pump. The resulting flow in the riser 16 opens the valve 58 which causes a water flow signal to be sent to the central office by customary or suitable transmitting apparatus T² and also bring 115 120 125 130

about the closing of a supplementary circuit α which includes a solenoid switch 24'. The latter moves to connect branch wires d' leading in parallel from the wires d , and since 5 the connection continues until the system is reset, the pump keeps going after the device 20 has been reset to non-pump-starting position by the boosted pressure in the system. In making a test it is desirable to 10 produce a condition like that which would exist if a sprinkler head actually opened; and yet if the water flow signal were transmitted the apparatus T^2 would be run down and would require manual resetting; and 15 this would also energize the solenoid switch 24' permanently, until manually released. It is, therefore, desirable to avoid these occurrences while the test is being made. The 20 test valve apparatus with its associated mechanism and electrical connections as shown in Figures 5, 6, and 7, accomplished this double purpose automatically when the operator at the central station sends the proper impulse along line L to close switch 44. In thus closing, the switch 44 establishes a circuit from power main M through wire e, the switch 44, wire f, the test valve motor 42, and wire g back to the power lines M. This starts the 25 valve motor 42 which by suitable gearing rotates the disk D' which in this instance is 30 illustrated with its depression 50 arranged opposite the crank pin 38, and vertically upward when in idle position (Figure 6). The initial turning of the disk D' causes the depression 50 to leave and the peripheral cam surface of the disk to pass under the roller 62 of an insulated arm 64 thereby raising the latter and setting an attached spring switch terminal f' against an unattached terminal h'. The terminal f' is connected to wire f, and the terminal h' to a wire h leading from wire e ahead of the solenoid switch 44, so 35 that this contact enables the current to continue through the motor after the solenoid S becomes de-energized, which happens very promptly after the initial impulse is received from the central station. Accordingly the motor continues to run until the disk has 40 made a complete rotation bringing the depression 50 again under the roller 62 whereupon the drop of arm 64 opens the terminals f'-h' and thus stops the motor 42.

During its rotation the disk, by pin 38 and the lever 36, has opened and closed a test valve 32' of the three way type. This valve is in the passage 66, 68 from the system to a pump controlling device 20' like device 20, and set to be actuated upon fall of pressure to a predetermined degree. When closed 45 the valve closes a discharge outlet 70 from 68 and the pump control device 20' to a drain 72, being held tightly to its seat by the system pressure, and at the same time opens 66 to 20' through its opposed valve seat 73, surrounding the stem 34'. As its stem is lifted

the valve 32' is transferred from its seat around outlet 70 to its seat 73 in the partition of the valve. This venting of the device 20' to atmosphere, with cutoff of system pressure insures its prompt drop to the actuating degree, and the start of the pump. The 70 system pressure beyond the valve 58 is barely disturbed for the slight leakage during the shifting of the valve 32' is not appreciable. The operation of the pump soon boosts the 75 pressure in the riser 16 below the valve 58 and this change is indicated at the central office by means of a pressure responsive signal transmitter T.

The test valve stem 34' is in two sections 80 with a pair of stiff diaphragm springs 34" connecting them and providing the necessary yield when needed.

If the pressure beyond the check valve 58 is 85 lower than that produced by the pump, the check valve will open under flow of the water and thus close the terminals 78, 80 of a spring switch which forms part of a self supervising circuit comprising two loops, both extending from one of the terminals to 90 the other, in one of which loops is a battery 82 and in the other of which is the solenoid switch of transmitter T^2 . When the terminals are open current flows in both loops, keeping the field of the solenoid energized 95 and its armature indrawn, but when the terminals are closed, as upon the opening of the check valve 58, the high resistance loop through the solenoid is short circuited permitting its armature to fall and release a 100 spring-actuated key 84. On this key are suitably arranged fingers which, as the key rotates, make and break the circuit through line L to give a distinctive water flow signal 105 at the distant station; and there is also finger 86, represented as insulated but not necessarily so, which near the end of the key's rotation closes the spring terminals of a switch 88. This completes a circuit α through solenoid switch 24' and as previously described 110 effects continuous operation of the pump.

During a test, however, the present invention provides for making the closing of the switch terminals 78, 80 ineffective to short circuit the loop through the solenoid of 115 transmitter T^2 . The wire j of one solenoid loop leading from terminal 78 is connected to a spring terminal j', projecting through the insulating holder 47' mounted in the motor casing 37, and tending to move toward its stop 90. Another terminal h' adjacent to terminal j' has its end h'' bent back over the end of terminal j'; and holds the latter away from its stop 90, when the disk D' is in the position shown in Figure 6. This terminal h' is connected to wire h which forms the continuation of the loop through the solenoid to terminal 80. The wire l also leading from terminal 78 joins a spring terminal l' which tends to rest against its stop 92. 120

The remaining terminal m' which is secured to arm 64, is connected with wire m running to battery 82 from which the loop continues along wire n to the terminal 80 of the water flow switch. When the roller is in depression 50 on the disk D' the terminals j' and k' are in contact as are also the terminals m' and l' , and the two loops of the self supervising circuit are in their normal relation, with the solenoid loop ready to be short circuited in case the water flow valve opens and closes the terminal 78, 80. This is the condition with the test valve closed and with the system idle and ready.

15 Upon the initial rotation of the disk D' when a test is started, the rise of the roller 62 and arm 64 as the cam surface comes under it, moves terminal m' with l' following still in contact until m' touches k' thereby 20 joining electrically the wires m and k . Further rise of the arm 64 draws m' away from l' as the latter reaches its stop 92, and also lifts the turned over end of k' away from j' as the latter is restrained by its stop 90. 25 Thus the battery and solenoid loops are connected and the terminal 78 of the water flow switch is cut out of the loop circuits. Accordingly, if flow consequent upon the booster pump's action during the test opens 30 the valve 58 the resulting closure of the terminals 78 and 80 does not short circuit the solenoid loop, and no water flow signal is sent, the key 84 is not released and the circuit through wires x to solenoid 24' is not 35 completed. When the test valve 32' is shifted back to its initial position and the system pressure acts upon responsive device 20' the pump will be stopped. At the same time, the terminals j' , k' , m' , and l' will be again 40 moved to bring j' and k' in contact, as well as m' and l' . The boosted pressure in the riser 16 below the check valve 58 will leak away through the pump glands, leaving the system ready for another test or for fire extinguishing action should the need arise, and the restoration of this condition after test is indicated at the central office by the device T sending a low pressure signal.

I claim as my invention:

50 1. Valve apparatus comprising a valve seating in the direction of its axis; a rotating element adapted in a single rotation to effect a complete cycle of operations of the valve; means connecting the valve and the said element for converting rotary motion of said element to motion of translation of said valve; power means for rotating said element; means for energizing said power means; and means controlled by said element for de-energizing the power means at the end of a complete rotation of said element.

65 2. Valve apparatus comprising a valve seating in the direction of its axis; a rotating element adapted in a single rotation to

effect a complete cycle of operations of the valve; a lever having connection with said valve and crank connection with said element, whereby rotary motion of said element effects motion of translation of said valve; power means for rotating said element; means for energizing said power means; and means controlled by said element for de-energizing the power means at 70 the end of a complete rotation of said element. 75

3. The combination with an automatic sprinkler system for fire protection having a pump for boosting the supply pressure and control means for said pump including a 80 device responsive to changes of system pressure, of means for testing said system comprising a passage for fluid under pressure communicating with said device, a valve set in said passage and adapted to be moved axially thereof to control pressure changes upon said device whereby the latter is actuated to start and stop said pump; means for moving said valve at will, comprising a 85 rotating element; means extending to a distance for setting said element in motion; and means associated with said element for stopping its movement at the end of a single rotation.

4. The combination, with an automatic 90 sprinkler system having a pump for boosting the supply pressure, a device responsive to change of pressure controlling operation of said pump, and signalling means responsive to flow consequent upon the operation of said 100 pump, of testing apparatus for effecting a change of pressure on said device to start and stop said pump; said apparatus comprising means controlling said signalling means whereby the latter is rendered incapable of transmitting a flow signal during 105 the test.

5. The combination, with an automatic 110 sprinkler system having a pump for boosting the supply pressure, a device responsive to change of pressure controlling operation of said pump, and signalling means responsive to flow consequent upon the operation of said pump for transmitting a signal to a distant station, of apparatus for testing 115 said system comprising a passage for fluid under pressure communicating with said device, a valve set in said passage and adapted, upon being moved, to effect change of pressure upon said device, whereby it is actuated 120 to start and stop the pump, means governing the movements of said valve comprising a rotating element which in a single rotation effects a complete cycle of valve operations, and means actuated by said element for rendering the signalling means incapable of 125 transmitting a flow signal during a test.

6. The combination, with an automatic 130 sprinkler system having a pump for boosting the supply pressure, and control means for

said pump including a device responsive to change of system pressure, of valve apparatus for testing said system, comprising a passage for fluid under pressure communicating with said device, a valve set in said passage and adapted, upon being moved, to effect change of pressure upon said device whereby it is actuated to start and stop the pump, means governing the movements of 5 said valve comprising a rotating element which in a single rotation effects a complete cycle of valve operations; and means for rotating said element.

10 7. The combination with an automatic sprinkler system having a pump for boosting the supply pressure, and control means for said pump including a device responsive to

changes of system pressure, of valve apparatus for testing said system comprising a 20 passage for fluid under pressure to said device, a valve in said passage whose movements control pressure changes upon said device and actuate it to start and stop the pump; means for moving said valve comprising a rotating element which in a single rotation 25 controls a complete cycle of valve operations, means extending to a distance for setting the element in motion, and means controlled by the element for stopping its motion at the end of its single rotation. 30

Signed at Providence, Rhode Island, this 17th day of October, 1924.
